UNITED STATES PATENT OFFICE.

ALBERT P. ECKHART, OF SHOHLA, PENNSYLVANIA.

RADIATOR.

Application filed April 22, 1925. Serial No. 25,098.

This invention relates to an improved engine radiator particularly designed for use on motor vehicles and seeks, among other objects, to provide a radiator which, as compared with an ordinary radiator of like size, will have superior cooling qualities.

The invention seeks, as a further object, to provide a radiator wherein the vertical tubes of the device will all be so disposed that air currents flowing through the radiator from front to rear thereof may impinge directly against each of said tubes.

And the invention seeks, as a still further object, to provide a radiator having a radiating plate unit removable at the back of the radiator so that access may be readily had to the water tubes for repairing said tubes, and wherein the tubes will be disposed to center said unit within the radiator shell. Other and incidental objects will appear hereinafter.

In the accompanying drawings:

Figure 1 is a front elevation of my improved radiator.

Figure 2 is a horizontal sectional view on the line 2--2 of Figure 1, looking in the direction indicated by the arrows.

Figure 3 is a vertical sectional view on the line 3--3 of Figure 1, looking in the direction indicated by the arrows.

Figure 4 is a detail perspective view showing one of the plates of the removable plate unit employed.

In carrying the invention into effect, I employ a shell including top and bottom tanks 10 and 11 connected by parallel side plates 12. The top tank is formed with a filler tube 13 normally closed by a screw cap 14 and formed on the tank at the rear side thereof is an inlet 15 while the bottom tank 11 is provided with an outlet 16.

Disposed between the top and bottom tanks is a core including a plurality of vertically disposed parallel water tubes 17 fixed to the confronting walls of the tanks 10 and 11 to communicate with said tanks. Thus, water entering the inlet 15 will flow into the tank 10 to thence descend through the tubes 17 into the tank 11, when the water will discharge through the outlet 16. As particularly shown in Figure 2, the tubes 17 are disposed in a transversely extending zig-zag row. As will be observed, all of the tubes are spaced transversely of the shell with respect to each other and thus no one of said tubes will form an obstruction in

front of any other of the tubes to prevent currents of air flowing through the radiator from the front to rear thereof, from impinging directly against the tubes. Accordingly, each of the tubes will be directly subjected to the cooling influence of the air currents with the result that less tubes are required to effect the cooling of the water in a radiator of a given size as compared with an ordinary radiator of like size wherein the tubes are alined from front to rear of the radiator core. By zigzagging the row of tubes, it is also possible to mount a greater number of tubes in a row between the side plates of the shell than were the tubes arranged in a straight line.

Suitably secured to the tubes 17 is a plurality of vertically spaced horizontal radiating plates forming a fixed radiating plate unit 18, and, as brought out in Figure 2 of the drawings, the rear edges of the plates are notched to conform to the zigzag contour of the row of tubes 17 so that V-shaped cavities are thus defined at the rear of the core between the angularly disposed portions of said row of tubes. Fitting between the top and bottom tanks 10 and 11 of the shell is a mating removable radiating plate unit 19, the parallel plates of which are connected by a plurality of vertical tie rods extending through said plates. These rods are of a length to be freely received between the confronting walls of the tanks 10 and 11 and serve to center the unit 19 between said tanks. The plates of the unit may be secured to the rods in any approved manner and, as shown in Figure 4, said plates are each notched to form a pair of V-shaped tongues 21. The tongues 21 of the several plates are, as shown in Figure 2, adapted to fit in the cavities at the rear of the core between the angularly disposed portions of the row of tubes 17, abutting said tubes, so that the plate unit 19 thus occupies said cavities to complete the symmetrical contour of the core while the tongues of the plates of said unit coast with the tubes for centering the unit transversely of the shell and limiting said unit against transverse movement. Extending freely between adjacent plates of the core units 18 and 19, near the upper and lower ends of the core, are pairs of tie rods 22 upon the rear ends of which are screwed nuts 23 clamping the unit 19 in position. Thus, as will be seen, by removing these nuts, the

unit 19 may be displaced at the rear of the radiator when access may be readily had to the tubes 17 for repairing said tubes.

The plates comprising the fixed unit 18 have openings arranged in rows paralleling and adjacent the indented marginal edges to receive the tubes 17 which may be soldered thereto or secured in any preferred way. The plates of the detachable unit 19 have their indented edge portions overlapping the indented edge portions of the plates of the unit 18. The tongues of one set of plates are disposed opposite the V-shaped spaces of the opposite set of plates and enter the depressions formed between adjacent rows of tubes.

Having thus described the invention, what I claim is:

A radiator, comprising top and bottom

tanks, tubes connecting opposing walls of the tanks and having a zigzag arrangement to define V-shaped depressions between adjacent rows of tubes, a plurality of plates disposed between the tanks and forming a fixed unit and having the inner edges indented to form tongues, and having openings arranged in rows adjacent and paralleling the indented marginal edges to receive the tubes, and complementary plates connected to form a removable unit and having their inner edges indented to define V-shaped tongues disposed to enter the spaces formed between the tongues of the fixed plates, the indented marginal edges of the two sets of plates overlapping.

In testimony whereof I affix my signature.

ALBERT P. ECKHART. [L.S.]
